UNITED STATES PATENT OFFICE.

ROSAMOND LILIAN KENNEDY, OF HYDE PARK, LONDON, ENGLAND.

BUST BODICE

Application filed June 24, 1927, Serial No. 201,271, and in Great Britain November 25, 1926.

This invention has reference to an improved bust-bodice designed to afford the wearer adequate and correct support while permitting perfect freedom of movement and presenting a more natural appearance than heretofore.

Bust-bodices have hitherto usually been constructed with a waist band intended to pass round the body of the wearer and to be fastened at the back or front, the breast supports being attached to the waist band and provided with suitable shoulder straps. It has been found that when the device is made to fit sufficiently closely to keep the breast supporting pieces in position, a lateral pressure or pull is produced of which the wearer is sensible in certain positions. There is also a tendency to press or flatten the breasts against the body. An object of the present invention is to obviate these defects and to provide a light and simple form of construction in which the combined effect of the various parts is to keep the supports in correct and comfortable position and to impart a natural appearance.

According to the present invention a bust-bodice is provided having breast supports constituted by two substantially triangular pieces of material overlapping or intersecting so as to have a common base line for a part of their length, each of said supports having attached at its outer corner a strap or lateral extension, elastic or otherwise, adapted to pass around the wearer's back and be connected to the inner corner of the same support or a point equivalent thereto on the base of the other support, such that with shoulder straps extending from the upper corner of each support to the outer corner thereof or an adjacent part the tension of said shoulder straps and the lateral extensions is taken along the inner sides of the supports.

In function, each breast support may be regarded as more or less separate and independent, inasmuch as the ends of the lateral extension passing around the wearer's back are connected respectively to the inner and outer corners of the support, while the shoulder strap serves to retain the whole in position. It is convenient however to stitch or join the two supports together where they cross or over-lap, and it will therefore be apparent that the two may be cut from a single piece of material without substantially affecting their function, provided the inner ends of the lateral extensions are attached to the

common base of the two supports at points substantially in prolongation of the inner sides of the supports. Thus, in all cases the tension of the shoulder straps and the lateral extensions is taken along the inner sides of the supports and tends to draw those sides nearer to the body and form a depression between the breasts, which are thereby supported separately and naturally.

It will also be seen that while the overlapping parts of the supports have a common horizontal base line, the remainder of the base of each support is free to move upwards instead of being held by attachment along the whole length to a waist-band as in constructions hitherto proposed, and the length of the shoulder straps is preferably adjusted so that the outer corners of the supports are lifted, to allow the outer side of each support to conform to the curvature of the breast. The overlap of the supports in front is preferably such that the inner points of attachment of the lateral extensions lie more or less vertically below the upper corners of the supports to which the shoulder straps are secured, so that a pull is produced opposing the lift of the shoulder straps and serving to keep the supports from being lifted up out of place.

The inner ends of the lateral extensions may be attached by means of buttonholed tabs secured to the supports and buttons on the ends of the lateral extensions or vice versa. Or, alternatively, these extensions may be permanently attached to the said points, but this necessitates the device being drawn on over the head and shoulders, or made separable at some other part.

The supports may be provided with pleats, darts, or tucks to give them the necessary fullness and the desired form.

One form of construction in accordance with the invention is illustrated in the accompanying drawings, in which:—

Fig. 1 is a view of the bust-bodice laid out flat, and

Fig. 2 is a view showing the device as it would appear in use.

Referring to these drawings:—

Two approximately triangular pieces A and A¹ of appropriate material such as silk or other soft textile fabric are secured together with their adjacent sides over-lapping to form the supports, and in order to impart a rounded contour thereto tucks or "darts" B are taken in the bases of the triangles and gradually diminish to about the centres of the

supports. It is to be understood that the supports may be given shape in any other manner or by the use of further tucks or "darts."

Secured to the outer corners of the supports

- 5 A and A¹ are lateral extensions C and C¹, preferably though not necessarily elastic, and arranged to pass around the back of the wearer and fasten to button-holed tabs D and D¹ respectively, that is to say the extension C
- 10 passes around the back and fastens to the tab D and the extension C¹ passes round the back in the opposite direction and attaches to the tab D¹, as will readily be seen by reference to Fig. 2. In the preferred construction shown
- 15 in the drawings these tabs D and D¹ are secured at the inner corners of the triangles, or, where the supports are cut to shape from a single piece of material, at the points where the inner sides of the triangles produced cut
- 20 the bases, these points it should also be noted, lying substantially vertically under the apices to which shoulder straps E and E¹ are secured, the other ends of the shoulder straps being attached to the outer corners of the supports.
- 25

The advantages of this form of construction will be readily appreciated by reference to Fig. 2. The pull of the shoulder straps is taken along the sides of the triangles, and

- 30 since the lateral extensions C and C¹ are attached at the corners the tendency is to form a depression between the breasts so that the latter are supported separately and naturally instead of being merely flattened against the
- 35 body.

Where the supports A and A¹ are made from separate pieces of material, they may if desired be made from two squares of material folded diagonally, the diagonal folds forming the bases of the supports, which may be stitched down along the over-lapping sides or merely sewn together at the corners, as desired.

What I claim is:—

1. A bust-bodice comprising breast supports constituted by two substantially triangular pieces of material intersecting in front so as to have a common base line for part of their length, a lateral extension strip attached to the outer extremity of each support and passing around the wearer's back and connected to the inner extremity of the same support, and a shoulder strap extending from the upper corner of each support to a point adjacent the outer corner thereof.

2. A bust-bodice comprising breast supports constituted by two substantially triangular pieces of material intersecting in front so as to have a common base line for part of their length, elastic lateral extension strips attached to the outer extremities of the supports and passing around the wearer's back in opposite directions and connected respectively to the bases of the opposite supports substantially vertically under the upper corners thereof, and shoulder straps extending from said upper corners to points adjacent the outer corners thereof.

ROSAMOND LILIAN KENNEDY.
